UNITED STATES PATENT OFFICE.

ALEXANDER SEIDLER, OF CHICAGO, ILLINOIS, ASSIGNOR, BY MESNE ASSIGNMENTS, TO F. C. AUSTIN MACHINERY COMPANY, A CORPORATION OF ILLINOIS.

INTERNAL-COMBUSTION BOILER.

Application filed August 30, 1918. Serial No. 252,067.

To all whom it may concern:

Be it known that I, ALEXANDER SEIDLER, a resident of Chicago, Illinois, have invented a certain new and useful Improvement 5 in Internal-Combustion Boilers, of which the following is a specification.

This invention relates to the burning of hydro-carbon to produce a flame of high temperature, and more particularly to the 10 generation of steam by means of a burner of this kind, or of any suitable character.

Generally stated, the object of the invention is to provide a novel and improved apparatus for converting hydro-carbon into 15 a combustible gas, and for advantageously burning the gas to produce a flame of high temperature.

Another object is to provide an improved construction and arrangement whereby 20 steam is generated by the combustion of the gas inside of the boiler, without the admission of air, sufficient air to support combustion being mixed with the gas or hydro-carbon vapor before it enters the 25 boiler, whereby pressure in the boiler is produced not only by the generation of steam, but also by the accumulation of the products of combustion.

It is also an object to provide certain 30 details and certain features of construction and combinations tending to increase the general efficiency and the desirability of an apparatus of this particular character.

To these and other useful ends the invention consists in matters hereinafter set forth and claimed.

In the accompanying drawings—

Fig. 1 is a longitudinal section of an internal combustion boiler and oil burning apparatus embodying the principles of the 40 invention.

Fig. 2 is an enlarged cross section on line 2—2 in Fig. 1.

Fig. 3 is an enlarged detail sectional view 45 of the burner, showing the automatic valve which forms a part thereof.

As thus illustrated, the invention comprises a boiler 1 of any suitable character, provided at one end with an opening 2 50 which is closed by the flanged union 3, the latter being rigid with the body 4 which encloses the burner. This body 4 is closed at its outer end by a removable plate 5, and has its inner end provided with a wall 6 55 having a tapered extension 7 which ter-

minates in the enlargement 8 which contains the explosion chamber 9 of the burner apparatus. This enlargement 9 has a flaring extension 10 by which to direct the flame into the water within the boiler. 60

A nozzle 11 is inserted through the plate 5, and into the funnel-like opening 12 formed in the partition plate 13, and this opening 12 terminates in a valve chamber 14, and the latter terminates in a tapered nozzle 15 that extends into the tapered extension 7 previously described, whereby this nozzle 15 extends nearly to the explosion chamber 9, but with space between the outer surface of said nozzle and the inner surface 65 of the extension 7, in order that heated air of the extension 7, in order that heated air may be mixed with the jet of gas which escapes from said nozzle. This is preferably accomplished by means of a pipe 16 which leads to the chamber 17 in the burner 70 head or body 4, it being observed that this chamber 17 communicates with the space around the nozzle 15, so that the air entering said chamber 17 will escape into the explosion chamber 9 where it will mix with 75 the gas and cause an explosion. The pipe 16 has a valve 18 which is operated by a rod 19 that extends downward into the valve chamber 14 (see Fig. 3), this chamber having a pivoted valve 20 which acts as a check 80 valve to prevent the back pressure of the explosions in the chamber 9 from extending backward into the mixing chamber 21 85 in the burner body. A spring 22 holds the rod 19 normally in a depressed position, so that when the valve 20 is raised by the pressure of the gas in the chamber 21, it will raise the rod 19 and thereby open the valve 18 and cause heated air to enter the chamber 17, as previously described. The 90 valve mechanism, comprising a hollow head or casing 23, is arranged to support the nozzle 11, and three pipes 24, 25, and 26, lead to said valve mechanism and communicate with the pipes 27, 28, and 29 in 95 the nozzle 11, so that all three of these pipes discharge through the end of said nozzle. Steam is supplied to the pipe 24, and naphtha or any suitable hydro-carbon is supplied to the pipe 25, while air is supplied to the pipe 26; and the valve mechanism is operated by the handle 30 to control the steam, and said mechanism is operated by the handle 31 to control the air, while an adjustable indicator 32 is pro- 100

105 110

vided for controlling the oil, it being understood that the valve mechanism is of any suitable, known, or approved character. The pipe 16 preferably communicates with 5 the pipe 26 to receive air therefrom for the previously described purpose.

The oil and air are supplied under pressure, of course, and these pressures and the steam pressure are controlled in 10 any suitable or desired manner, so that the oil and steam or air, or the oil with both the steam and the air, are projected from the nozzle 11 against the valve 20, and the hydro-carbon vapor thus 15 formed fills the mixing chamber 21 to form the gaseous mixture. The valve 20 opens under pressure, of course, and allows a quantity of the mixture to escape through the nozzle 15 into the explosion chamber 9, and 20 said valve in opening automatically opens the valve 18 and thereby admits air to the said explosion chamber 9, thereby forming a highly explosive mixture. It will be understood that after the burner is started the 25 entire structure becomes highly heated, so that the gases, under pressure, when they enter the hot chamber 9, are immediately ignited and caused to explode, and the force of the explosion closes the valve 20 against 30 the pressure of the supply of gas or vapor. Then, as soon as the pressure in the chamber 9 is reduced, the valve 20 is again opened by the pressure in the chamber 21, and another explosion is produced. These 35 explosions, it will be understood, follow each other with such rapidity that the combustion of the gas or gaseous mixture is practically continuous; thereby forming a flame of high temperature which is blown from the 40 funnel-shaped extension 10 directly into the water. This produces steam, of course, and the combustion of the gases produces products of combustion which add to the general pressure in the boiler.

45 A water pipe 33 is provided and arranged to connect with the pipe 34 which leads to the boiler. A pipe 35 connects with the pipe 34, between the boiler and the valve 36, which latter is in the main water supply 50 pipe. The pipe 35 is provided with a valve 37, and when the latter is opened, the contents of the boiler will be blown out through the pipes 34 and 35, in a manner that will be readily understood.

55 A pressure gage 38 can be applied to the chamber 21 to indicate the pressure in this chamber, it being understood that this pressure must always exceed the general boiler pressure, or otherwise the combustible mixture, formed by mixing the steam and air and hydro-carbon, could not force its way into the explosion chamber 9, and no combustion would take place. Of course, though, as previously stated, each explosion 60 in the chamber 9 momentarily increases the

pressure in this chamber to a point above the boiler pressure and above the pressure of the steam and air and oil supply, and it is this that is relied upon to close the valve 20 to prevent back pressure from escaping 70 from the boiler. The different pressures, it will be understood, can be regulated by the different valves to insure the desired results.

From the foregoing it will be seen that the process involves the formation of a primary mixture, by the mixing of hydro-carbon vapor with steam or air, or with both, in the chamber 21, and also involves the formation of a secondary mixture in the explosion chamber 9, inasmuch as the combustible 75 mixture discharged into the chamber 9 from the nozzle 15 is thereafter diluted with air, or with some suitable non-inflammable gas, preferably warm or hot, thereby to form a highly explosive mixture. The proportions 80 in which the different fluids are mixed, and whether steam or air, or both, are used, will depend upon the conditions and upon the character of the flame desired, and these 85 things are, or may be, regulated from time to time, it will be understood, in order to obtain the desired results.

Thus the explosions in the explosion chamber 9 alternate with the intermittent preponderance of pressure in the mixing or 90 vaporizing chamber 21, as the pressure in the latter must rise intermittently to a point above that of the main supply of generated fluid pressure in the pressure chamber of the boiler 1 previously described. Of course, 95 when an explosion occurs in the chamber 9, the pressure in the latter is momentarily greater than in the chamber 21, so that the valve 20 is closed, as explained, to prevent the back fire, so to speak, from reaching the 100 supply of mixture in the chamber 21, and to prevent premature ignition of said mixture.

What I claim as my invention is:—

1. The combination of a boiler for containing water to generate steam and means 110 for causing combustion within the boiler so that the products of combustion serve to augment the pressure derived from the generation of steam, said means comprising an explosion chamber communicating with the 115 interior of the boiler, a nozzle arranged to discharge into said chamber instrumentalities for supplying hydrocarbon with air or steam, or with both, a mixing chamber in which the hydrocarbon and air or steam, or 120 both, are mixed to form a primary mixture, a valve automatically opened by the pressure in the mixing chamber to admit the mixture to said nozzle, and means automatically controlled by said valve to admit air 125 to said explosion chamber, said valve being adapted to be automatically closed by the explosion to prevent the back pressure from entering said mixing chamber.

2. In a pressure generator, the combina- 130

tion of a pressure chamber, an explosion chamber arranged to deliver fluid pressure to said pressure chamber, a mixing chamber arranged to deliver a combustible mixture to 5 said explosion chamber, controlling means whereby the mixture is intermittently admitted to said explosion chamber to cause successive explosions therein, said explosion chamber being adapted to be maintained at 10 sufficiently high temperature by the combustion therein to ignite the successive charges of mixture admitted thereto, instrumentalities for supplying fluids under pressure to said mixing chamber, and means 15 automatically controlled by said controlling means to admit air to said explosion chamber to dilute the mixture admitted thereto by said valve.

3. In a pressure generator, the combination of a pressure chamber, an explosion chamber arranged to deliver fluid pressure to said pressure chamber, a mixing chamber arranged to deliver a combustible mixture to said explosion chamber, controlling means 20 whereby the mixture is intermittently admitted to said explosion chamber to cause successive explosions therein, said explosion chamber being adapted to be maintained at sufficiently high temperature by the combustion therein to ignite the successive charges of mixture admitted thereto, and instrumentalities for supplying fluids under pressure to said mixing chamber, said explosion chamber comprising a nozzle extending 25 into said pressure chamber, said mixing chamber having a second nozzle containing said controlling means and extending into said first nozzle, and said instrumentalities comprising a third nozzle disposed in position to discharge into the second nozzle with 30

a passage whereby the discharge from the third nozzle is turned back into said mixing chamber.

4. The combination of a steam generating boiler, a mixing chamber for converting hydrocarbon fuel into a highly explosive gaseous mixture, a valve chamber provided with a valve adapted to permit passage of the mixture when a certain pressure is reached in said mixing chamber, an explosion chamber beyond said valve chamber and communicating directly with the liquid in the boiler, and means for admitting additional air to said explosion chamber, said valve acting automatically to intermittently admit 45 charges of the mixture into said explosion chamber and to prevent back-fire from said explosion chamber to said mixing chamber. 50

5. The combination of a steam generating boiler, a fuel mixing chamber, an explosion chamber, a valve chamber intermediate said mixing and explosion chambers, and means for admitting air separately to the explosion chamber, said valve chamber being provided with a valve controlled by the relative pressures in the mixing chamber and the explosion chamber whereby an excess of pressure in the mixing chamber forces a charge into the explosion chamber and an excess of pressure in the explosion chamber closes said 60 valve and the alternation of said excessive pressures rapidly opens and closes the valve to cause successive explosions from which the heat and products of combustion are directed into the boiler, the action of said 65 valve serving to control the admission of the separate air supply to said explosion chamber. 70 75

ALEXANDER SEIDLER.
